N. S. BEMENT

TRAFFIC LIGHT

Filed Aug. 24, 1926

UNITED STATES PATENT OFFICE.

NEWTON S. BEMENT, OF ANN ARBOR, MICHIGAN.

TRAFFIC LIGHT.

Application filed August 24, 1926. Serial No. 131,288.

In the operation of automobiles much difficulty is experienced in obtaining a satisfactory scheme for lights which will be suitable for driving both in town where the traffic is heavy and the streets are lighted and also in the country where entirely different conditions prevail, as is well understood. The headlight in common use with parabolic reflector and plain glass lens is perhaps as satisfactory as anything devised for a driving light on country roads or outside of cities and when not in traffic. A car equipped with such lights should also be equipped with dimming devices sufficiently effective to thoroughly dim the lights when on lighted streets in the city and when meeting machines on country roads so that they may be made absolutely non-glaring. Such dimming, however, renders the lamp inefficient since when dim there is not sufficient light for safety in driving.

The object of my said invention, therefore, is to provide a light which I term a "traffic" light, consisting of a lamp to be placed preferably on a forward part of the left front fender or nearly in that position, and so wired that once the master switch controlling it from the dash has been connected, a second switch in the circuit is closed automatically with the dimming of the headlights.

A further object of my invention is to construct such a device which will project a powerful light, sharply defined and free from glare or side rays. Another object is to construct the traffic-light so that the rays projected may be horizontal to illuminate the full width of the street or roadway, or, rotated sufficiently to illuminate the side of the roadway. Another object is to prevent any rays from projecting above the center line of the headlight when in the horizontal position. Still another object is to provide for the operation of the traffic light in conjunction with the dimming of the ordinary headlights.

Referring to the accompanying drawings, which are made a part hereof and on which similar numerals designate similar parts in the several views:

Figure 1 is a side elevation of a headlight attached to the fender of an automobile,

Figure 2, a front elevation of the same, Figure 3, a detail front elevation on a larger scale,

Figure 4, a longitudinal section through the headlight and its mounting.

Figure 5, an elevation similar to Figure 3 with the body revolved 90 degrees, 60

Figure 6, a detail perspective of the frame for supporting the deflectors,

Figure 7, an elevation of one of the deflectors,

Figure 8, a detail section on the line 8—8 65 of Figure 7,

Figure 9, a diagrammatic front elevation of an automobile equipped with my improved traffic light, and

Figure 10, a wiring diagram.

In the drawings, the numeral 10 denotes the automobile equipped with the usual headlights 11, and 12 denotes the left front fender upon which is mounted the traffic-light which is composed of a projector 14 and a signal or running light 15. I have found by experience that the ordinary headlight with parabolic reflector and plain lens is the most satisfactory driving light when outside of the city and when not in traffic, 80 however, a car equipped with my improved traffic light should also be equipped with a dimming device for the headlights arranged in such a way that when the headlights are dimmed the traffic light is lighted.

The projector comprises the parabolic reflector 16 and lamp 17 of the usual construction. The reflector 16 is secured by bolts 18 to the back 19 of the projector which is flanged to fit over the rear end of a cylindrical body portion 20 which extends a considerable distance forward of the front of the reflector when assembled. The forward end is closed by a ring 21 which also confines the lens 22 which is preferably a disk of plain glass. As a means of projecting a powerful light straight ahead without permitting any glare or side rays, I employ a series of deflectors 23 securely mounted in a skeleton frame 24 located within the cylindrical body portion 20 between the front edge of the reflector 16 and the lens 22. The skeleton frame is made of a stamping of sheet metal having a ring 25 with extensions 26 extending at right angles therefrom with their ends 27 again bent at right angles and bolted to a separate ring 28 forming a cage in which the deflectors are secured by wiring as shown in Figure 6, to the rings 25 and 28 and by soldering. Each deflector comprises 100 a sheet of extremely thin hardened aluminum or brass, approximately 1/100 of an

inch or less in thickness and of a mathematically predetermined length, slightly curved in cylindrical form with its concave surface 29 highly polished and the convex surface 5 treated with a coating of metal filler 30 which renders it totally non-reflecting. The straight edges of each deflector is bent at approximately right angles as at 31 to strengthen the plate.

10 Owing to the extreme thinness of the plates 23 I find it best to curve them in the frame 24 by providing each plate with a loop of wire 23' in each corner, as shown in Fig. 6, which wires are passed through openings in the members 25 and 28 and secured by a drop of solder 50 put into the opening, (see Figure 6). The loose ends of the wires are then cut off. The deflectors are all of the same curvature and of the same length axially, but owing to the cylindrical form of the body portion 20, they gradually diminish in width from the center towards the top and bottom as shown in Figure 5. In Figures 1, 2 and 3, the plates are shown approximately 20 vertical, which owing to the coating of metal filler 30 on the convex side, direct all of the rays which strike the concave surface 29 to the right, the direct rays from the lamp 17 passing between the plates unobstructed and 25 straight ahead. This position of the plates illuminates the roadway from an imaginary line drawn straight ahead of the projector and to the right, but leaves the left side of the roadway dark.

30 When driving on city streets it is necessary to have sufficient light without blinding an approaching motorist or pedestrian. In order to accomplish this result, I mount the body portion 20 of the projector in such 35 a manner that it may be revolved axially 90 degrees which positions the deflectors 23 with their concave surfaces down thereby directing the light rays downward the full width of the roadway and preventing any 40 rays from passing above the plane of the top of the projector, which is usually about 37 inches above the roadway and too low to blind another motorist or pedestrian approaching. The projector is mounted on 45 top of the frame 32 of the "running" or "go" signal 15 by means of a band 33 which passes around the portion 20 and has its ends secured to the sides of the signal 15 by screws 34 which when tight hold the projector firmly, but which may be loosened to 50 permitting the projector to be rotated to change the direction of the rays. This signal operates in conjunction with the customary "stop" signal on the rear of the car and controlled by the brake pedal to be lighted when 55 the "stop" light is burning and to extinguish as when the "stop" light is extinguished. As it is customary to display a "red" light for danger or "stop", I employ green celluloid

35 in the signal 15 to designate that the car 65 is being stopped and it is safe to pass in front of it.

The signal together with the projector is mounted on the fender 12 of the car by any suitable bracket 36 which will permit of 70 slight adjustments vertically and horizontally.

It will be obvious to those skilled in the art that various changes may be made in my device without departing from the spirit of 75 the invention and therefore I do not limit myself to what is shown in the drawings and described in the specification but only as indicated in the appended claims.

Having thus fully described my said invention, what I claim as new and desire to secure by Letters Patent, is:

1. A light deflector for traffic lights comprising a series of comparatively thin metal plates having concave reflecting surfaces and convex non-reflecting surfaces, and flanges on the straight edges of each of said plates, substantially as set forth.

2. A light deflector for traffic lights comprising a series of curved, thin metal plates 90 each of the same radius, short flanges on the straight edges of each plate, a reflecting concave surface and non-reflecting convex surface on each plate and a removable frame 95 confining said plates, substantially as set forth.

3. A deflector for traffic lights comprising a series of cylindrically curved, parallel plates each having a reflecting concave surface and a non-reflecting convex surface, 100 and flanges on each plate to reinforce the same, substantially as set forth.

4. A traffic light for automobiles comprising a cylindrical projector, a reflector, a source of light, a lens, and light deflectors comprising a series of cylindrically curved, parallel plates with their axes parallel with said projector, said plates varying in width and having reflecting concave surfaces and non-reflecting convex surfaces and integral flanges on each plate, substantially as set 110 forth.

5. A traffic light for automobiles comprising a cylindrical projector, a reflector, a source of light, a lens, and light deflectors comprising a series of cylindrically curved, parallel plates, a cage for holding said plates, aligned openings in said cage, wires attached to the corners of said plates and adapted to enter certain of said openings, and means such as solder for confining said wires in said openings, substantially as set forth.

In witness whereof, I have hereunto set my hand at Ann Arbor, Michigan, this thirteenth day of August, A. D. nineteen hundred and twenty-six.

NEWTON S. BEMENT.
